Filed Jan. 25, 1957, Ser. No. 636,415

6 Claims. (Cl. 230—139)

This invention relates generally to rotary compressors, and with regard to certain more specific features, to an internal-combustion, alternating piston rotary compressor for supplying hot gas including air to units such as gas turbines and the like.

Among the several objects of the invention may be noted the provision of a rotary compressor powered by internal combustion and operative by positive volumetric displacement, although having a variable compression ratio for combustion; the provision of an efficient internally powered compressor of the class described having superior pressure-speed characteristics determined by said variable compression ratio; the provision of a compressor of the class described in which each piston is operative for both power and compressing events, thus minimizing the number of parts required and resulting, for a given capacity, in a comparatively compact, light-weight and low-cost machine; and the provision of a compressor of this class having inherent substantial dynamic balance between its rotating parts. Other objects and features will be in part apparent and in part pointed out hereinafter.

The invention accordingly comprises the elements and combinations of elements, features of construction, and arrangements of parts which will be exemplified in the structures hereinafter described, and the scope of which will be indicated in the following claims.

In the accompanying drawings, in which several of various possible embodiments of the invention are illustrated,

Fig. 1 is a diagrammatic axial section of an eight-piston machine illustrating one form of the invention;

Fig. 2 is a cross section taken on line 2—2 of Fig. 1;

Fig. 3 is a diagrammatic view similar to Fig. 2 but showing a subsequent position of parts and including a showing of a turbine to be supplied with gas;

Fig. 4 is a cross section taken on line 4—4 of Fig. 1;

Fig. 5 is a view similar to Fig. 2 but illustrating a modified six-piston form of the invention;

Fig. 6 is a diagrammatic view similar to Fig. 5 but showing a subsequent position of parts; and,

Fig. 7 is a cross section similar to Fig. 4 but illustrating parts corresponding to the modified form of the invention shown in Figs. 5 and 6.

Corresponding reference characters indicate corresponding parts throughout the several views of the drawings. Diagrammatic views are used herein for clarity, further detailed features of certain subcombinations of parts used having been disclosed in my various prior patents, including 2,638,880; 2,680,430; 2,687,609; 2,736,328 and 2,756,728. Various sealing means between relatively moving parts, known to the art, are not shown. Also for purposes of clarity and description and ease of reading the drawings, certain sets of pistons are identified by arbitrary stippling, and others are not. This stippling has no other significance.

Various machines, such as gas turbines, for example, require a substantial volume of a working medium such as a hot compressed gas, a part of which may be air. Reciprocating positive displacement compressors, because

2

of their complexities, are not ideal for producing such a medium in quantity. Nor are centrifugal compressors advantageous, because of their nonpositive displacement characteristics. By means of the present invention, the advantages are obtained of an inherently dynamically balanced comparatively small and efficient rotary machine having a single set of positive displacement elements for production of power and compression, having characteristics of quick response to variations in requirements for a supply of hot operating gas by other units.

Referring now more particularly to Figs. 1—4, which show a preferred form of the apparatus, there is shown in general at numeral 1 a toroidal or annular cylinder formed by an outside ring 3, to which are bolted internally flat side cheeks 5 and 7. The latter have extensions forming sleeve bearing portions 9 and 11, respectively, for rotatable quills 13 and 15. Adjacent ends of the quills 13 and 15 are formed as abutting rings 17 and 19, respectively, which have suitable running sealing means (not shown, but see Patent 2,736,328). Thus the toroidal cylinder 1 has a rectangular cross section formed by the inside face of the ring 3, the inside planes of the cheeks 5 and 7, and the coextensive outside cylindric forms of the rings 17 and 19. Ring 17 carries four pistons A, B, C, D, spaced at 90° intervals. These pistons are of substantially the same rectangular cross-sectional form as the cylinder 1 and have sealing means (not shown, but see Patent 2,756,728). Ring 19 carries four pistons W, X, Y, Z, spaced at 90° intervals. These pistons are also of substantially the same rectangular cross-sectional form as the cylinder 1 and carry similar suitable piston ring sealing means. Thus the pistons A, B, C, D on ring 17 interdigitate with pistons W, X, Y, Z on ring 19 (see Fig. 2).

The quills 13 and 15 have extensions 21 and 23, respectively, to which are splined hubs 25 and 27, respectively, the same being locked in proper splined positions, by fastening nuts 29. The splines are numbered 2. The hubs 27 and 25 carry identical flywheel elements 31 and 31' which, if desired, may be of the variable inertia type such as shown, for example, in said Patent 2,638,880; or these flywheels may be of the constant inertia type such as shown in said Patent 2,687,609. The hubs 25 and 27 also respectively carry identical spiders 33 and 35, one of which (35) is shown in solid end elevation in Fig. 4 and one of which (33) is shown in dotted elevation.

The reverse-locking parts attached to spider 35 are to be described below, and those on spider 33 are to be understood to be identical in form and operation. The index characters employed for describing those on spider 33 will be the same as those for the parts on spider 35, except that the former will be primed. Detailed description of the parts associated with spider 35 will therefore be sufficient.

Referring to Fig. 4, spider 35 is constituted by four arms, each of which carries a rotary pin 37 in needle bearings 39 (see Fig. 1). Each pin supports a bell crank 41, having one arm 43 supporting a fixed pin 45 which carries a follower roller 47 on bearing 46. Another arm 49 of each bell crank is slotted, as shown at 51, and contains a drawbolt 53. A coil spring 55 is wound around opposite ends of each pin and anchored at its ends by studs 57. A bale portion 59 of each spring reacts against the respective arm of spider 35. Each pin carries a polygonal head 61, adapted to be engaged by a wrench. Thus, by loosening the drawbolt 53, the pin 37 may be wound, so as to wind or tension the spring 55. After winding, the drawbolt is tightened, whereupon each bell crank 41 becomes biased in a clockwise direction (Fig. 4). This forces each follower roller 47 against a cam track 71, further described below.

Bearing sleeve 11 is flanged, as shown at 63, for receiving a bolted assembly of ring parts 65, 67 and 69 for supporting an inwardly directed cam track 71. Correspondingly indexed but primed parts are attached to the bearing sleeve 9 for supporting an inwardly directed cam track 71'. The cam tracks 71 and 71' are preferably mounted, so that their shapes are axially aligned. The spider 33, bell cranks 41' and follower rollers 47' are mounted to be as shown by the dotted lines in Fig. 4 when the groups of pistons A, B, C, D and W, X, Y, Z are related as shown in Fig. 2.

Ring 65 also carries a bearing 66, for supporting the extension 23 of quill 15. A corresponding bearing 66' in ring 65' supports the extension 21 of quill 13. Thus it may be seen from Fig. 4 that the springs 55 and 55' bias the respective sets of follower rollers 47 and 47' against the respective cam tracks 71 and 71', the latter showing in Fig. 1.

Each cam track 71 and 71', as illustrated in the case of cam track 71 in Fig. 4, is essentially square in form, having four flats 73 and four rounded or filleted corners 75. It will be understood that cam track 71' being located directly behind cam track 71 as viewed in Fig. 4, is not visible in that figure but appears in Fig. 1. The relationship of the parts is such (Fig. 4) that clockwise rotation of the spiders 35 and 33 is permitted, but each has a reverse-locking position. The reverse-locking position of spider 35 appears in solid lines in Fig. 4. Thus ring or rotor 19 (to which the spider 35 is attached) and its pistons W, X, Y, Z are reverse-locked. This is for the reason that thrusts on the follower rollers 47, due to any tendency toward reverse rotation in the Fig. 4 solid-line position, are at (or so near) a right angle with respect to one of the flats 73 as to prevent anticlockwise rotation of each bell crank 41 (in the case of spider 35). At this time the corresponding connected spider 33 and follower rollers 47' pass through the dotted-line position shown in Fig. 4 and the pistons W, X, Y, Z on ring 19 are in the intermediate position shown in Fig. 2.

At numeral 77 is shown a drive shaft carried on sets of bearings 79 and 81 within the quills 13 and 15. Bolted to the hub 35 is a gripping assembly 83 for one end of a drive spring 85. A second gripping assembly 87 is provided for the opposite end of this spring, said assembly 87 being attached to the shaft 77 by the set screw gripping arrangement shown at 89. Corresponding parts indexed with primed numbers connect the hub 25 with the other end portion of shaft 77. The springs 85 and 85' are in neutral or unstressed position when the parts are in the positions illustrated in Figs. 2 and 4. This position of parts will hereinafter be referred to as a neutral position. The shaft 77, with the operating parts of the auxiliaries connected thereto, has sufficient moment of inertia that it will maintain a substantially constant angular velocity while delivering or receiving energy from the rotor systems with which it is connected by springs 85 and 85'.

Referring to Figs. 2 and 3, there is shown diagrammatically at numeral 91 an ignition device such as a constantly energized glow plug, countersunk into the inner face of cheek 5 so as to allow the pistons to pass. Further details regarding such ignition devices are unnecessary, since such are known in the art. At numeral 93 is a fuel inlet port, to which a suitable carburetor or fuel injection device is attached, not shown because it may be any of known type. At numerals 95 and 97 are shown air inlet ports, connected to the atmosphere. At 99 is shown an exhaust gas outlet port, and at numerals 101 and 103, air exhaust ports. The ports 99, 101 and 103 are connected to a gas manifold 105 supplying appropriate apparatus 107 for using the gas and air from ports 99, 101 and 103. This may be a gas turbine, such as illustrated diagrammatically at 107. At numeral 109 is shown a scavenging auxiliary exhaust port connected to the atmosphere.

Referring to Fig. 2, the bracketing arrow P indicates the 180° portion of the machine, throughout which power events occur, and bracketing arrow G indicates the 180° portion of the machine throughout which air compression events occur. Ports 93 and 99 subtend the power section P. Ports 103 and 95 subtend the compressor section G. Ports 103 and 97 subtend what will be called a subsection of section G and ports 95 and 101 subtend what will be called another subsection of section G. Operation is as follows, referring to Figs. 2 and 3, assuming that the machine is in operation:

Pistons W, X, Y, Z are reverse-locked, in view of the reverse-locking of spider 35 and follower rollers 47 (Fig. 4). This is due to the back pressure on piston W caused by an explosion event occurring between pistons W and B. This pressure is in excess of compression pressure between pistons A and W. The ignition means 91 has previously ignited fuel and caused said explosion event. But means 91 is shielded from igniting fuel under compression between pistons A and W. The pistons A, B, C, D are being advanced clockwise, their corresponding spider 33 and follower rollers 47' having moved from a prior reverse-locked position thereof to the dotted-line position shown in Fig. 4. Thus the explosion event occurring between pistons W and B drives pistons A, B, C, D, reaction being provided by piston W, which is reverse-locked. Spent gas from a previous explosion event is being compressed between pistons B and X, and travels out of port 99 to the turbine 107. A suction event (through port 93) is also occurring between pistons A and Z, drawing in carbureted fuel gas or vapor through port 93.

An air suction event is occurring between pistons X and C, air being drawn in through port 95. Air is also being drawn in between pistons D and Y through inlet port 97. Air drawn in from the atmosphere during a prior suction event is being compressed between pistons C and Y and is being driven out through port 101 to the turbine 107. Air is also being compressed between pistons D and Z and being driven out through port 103 to the turbine 107.

Thus at the instant under discussion, pistons A, W, B are engaged in gas power events in the arcuate power section P of the machine, and pistons D, Y, C are engaged in air compression events in the arcuate compressor section G of the machine. Pistons Z and X are engaged in both sets of events, respectively, being interposed between ports 93 and 103 on the one hand and 99 and 95 on the other hand. Piston X also covers scavenging port 109. As will appear, each piston passes successively and repeatedly through all gas power and air compression events.

As the explosion between pistons W and B progresses, its pressure decreases but the compression between pistons A and W increases, so that ultimately the reverse-locked position of piston W (and connected pistons X, Y, Z) becomes driven clockwise from the position shown in Fig. 2 to the position shown in Fig. 3, wherein the positions of the pistons W, X, Y, Z and A, B, C, D have been interchanged. This is due to the gas-buffered collision event between pistons A and W. For further particulars, if desired regarding such action, said prior patents may be consulted, particularly Nos. 2,638,880 and 2,680,430. During this interchange, piston W has been pushed from its reverse-locked position and piston A has assumed it, while at the same time the compressed gas between pistons A and W has been exposed to ignition from the temporarily unshielded plug 91, resulting in an explosion event between pistons A and W in Fig. 3, with a gaseous compression event between pistons A and Z. Pistons A, B, C, D are then reverse-locked (Fig. 3). At this time, spent or exhaust gas is being driven from between pistons W, B into port 99, and compressed air is being driven through outlet ports 101, 103 between pistons X and C, and Y and D, respectively. A fuel suc-

tion event is occurring through port 93 and between pistons D and Z. Air suction events are occurring through ports 95 and 97, between pistons X and B, and Y and C respectively. In the position of parts shown in Fig. 3, the spider 33, attached to pistons A, B, C, D, has advanced to the reverse-locked position shown in Fig. 4 for spider 35. Spider 35, along with its pistons W, X, Y, Z, has receded from a reverse-locked position.

The cyclic action as described continues indefinitely, each piston successively passing through all gas suction, compression, explosion and exhaust events in section P of the machine, and then successively through all air suction and compression events in section G, the equal rotor systems connected with pistons A, B, C, D and W, X, Y, Z, respectively, alternately assuming reverse-locked positions. The result is a substantially continuous pulsing of both fuel exhaust gas and air to the turbine 107.

The purpose of the auxiliary gas exhaust port 109, which is connected to atmosphere, is to permit scavenging during the gas exhaust event of any excess of gases not accepted by the turbine 107 from exhaust port 99 and which might otherwise interfere with an efficient completion of the exhaust event.

Assuming that the machine is in operation as above described, there is then theoretically no requirement for the shaft 77. The practical purpose of the shaft is to effect starting and to drive any auxiliaries needed, such as generators, fuel, oil, pumps, or cooling fans and the like (not shown because conventional ones may be employed). The alternately rotary and differentially moving systems drive the shaft 77 through the respective spring connections 85 or 85', the springs winding and unwinding to effect driving, and permitting the relative or differential motions between pistons W, X, Y, Z and A, B, C, D during their cyclic actions above described. Further details as to this type of differential driving action may be found in said Patent 2,736,328. Other gear or hydraulic differential driving means may also be used (see Patents 2,638,880 and 2,680,430 for gear means, and 2,756,728 for hydraulic means). The flywheels 31 serve both to aid in bringing the successive pistons into reverse-locked positions and to minimize velocity changes in shaft 77. When the shaft is used for starting purposes, the starter attached to it (not shown) is caused simply to rotate it at a suitable cranking speed, which through springs 85 and 85' initiates the cyclic actions described. The required relative motions between the systems of pistons A, B, C, D and W, X, Y, Z are incipiently initiated by the differences in resistances between the sets of follower rollers 47 and 47' in passing around their respective cam tracks 71 and 71'. At this critical cranking speed, corresponding to the natural frequencies of oscillatory motions between the rotary systems and the shaft, the relative oscillations of the rotor systems build up until power events are initiated and continue in response to repeated explosive action.

In Figs. 5-7 is illustrated a six-piston form of the machine, which in proper section appears essentially such as shown in Fig. 1, and a redrawing of that figure is therefore unnecessary, particularly inasmuch as all of the points of departure of this form can be described from said Figs. 5-7. In this case, rotor 17 carries only three pistons L, M, N, and rotor 19 carries only three pistons R, S, T, the machine being divided into a 240° power section U and a 120° compressing section V. Said angles define angles of action. The same type of ignition device 91 is used in cheek 5. However, a fuel inlet port 111, a gas exhaust port 113 and a scavenger port 119 are changed in position, as shown. The number of air inlet and outlet ports is halved, an air inlet port 115 being adjacent ports 113, 119 and an air outlet port 117 being adjacent ports 111. Ports 111, 113 subtend the power section U and ports 115, 117 subtend compressor section V. The ports 111 and 117 are spaced to accept a piston

between them when the piston is reverse-locked (see piston T, for example); and ports 113 and 115 are spaced to accept a piston between them when the piston is reverse-locked (see piston S, for example).

Referring to Fig. 7, it will be seen that in this case the hub 27 carries a three-legged spider 121, carrying three sets of spring-pressed follower roller systems 55, 41, 47 such as above described. Correspondingly, the hub 25 at the other end of the machine (not appearing in Fig. 7) carries a three-legged spider 123, carrying three sets of spring-pressed follower roller systems 55', 41', 47', such as above described. In this case the cam tracks (the one shown in Fig. 7 being numbered 125 and there being another coaxially positioned behind it) have only three flats 127 and three filleted corners 129, providing three reverse-locking positions such as shown in solid lines in Fig. 7. The intermediate positions are shown by the dotted lines in Fig. 7 representing parts 55, 41' and 47'. The gas exhaust port 113 and air exhaust port 117 are connected by means of manifold 131 with the gas turbine 107.

Operation of the alternate form of the invention is as follows, referring to Figs. 5 and 7:

Pistons R, S, T, connected with spider 121, are in reverse-locking positions, while pistons L, M, N are moving clockwise. A suction event drawing in fuel through port 111 is occurring between pistons T and L. A gas compression event is occurring between pistons L and R. The explosion event is occurring between pistons R and M which holds system R, S, T reverse-locked to provide the necessary reaction. Gas is being exhausted from between pistons M and S through exhaust port 113 and is being delivered to the turbine 107. At the same time, air is being compressed between pistons T and N and driven out of the air exhaust port 117 to turbine 107.

In time, the pressure between pistons R and M decreases and the compression between pistons L and R increases sufficiently to remove pistons R, S, T from their reverse-locked positions shown in Fig. 5, pistons L, M, N taking up reverse-locked positions, as shown in Fig. 6. In the meantime, the compressed gas between pistons L and R has been exposed to the ignition plug 91 to produce an explosion (Fig. 6) between pistons L and R in Fig. 6. Gas is being exhausted between pistons R and M through port 113 for delivery to turbine 107. Fuel gas compression at this time occurs between pistons T and L. Fuel gas suction occurs through port 111 into the space between relatively receding pistons T and N. Air is being drawn into port 115 between relatively receding pistons M and S, and compressed air is being driven from between approaching pistons S and N through port 117.

The preferred form of the invention, as shown in Figs. 2-4, is used in those cases in which for a given power consumption a larger amount of air is desired at relatively lower maximum pressures; whereas the form of the invention shown in Figs. 5 and 6 is employed where for a given power consumption a smaller amount of air is required at relatively higher maximum pressures. The reason is that for a given set of power events in Figs. 2-4, two air compression events are brought about by one explosion event; whereas in the case of Figs. 5-7, only one air compression event is brought about by one explosion event. Other things being equal, substantially more air is being moved by the same power in the form of Figs. 2-4 as compared to the air being moved in the form of Figs. 5-7; therefore the ability to produce higher air pressure in the latter case. Also, in the Figs. 5-7 form of the invention, a higher compression ratio may be maintained in the power section U than is the case in the power section P in the form of Figs. 2-4. This may be desirable under some circumstances.

It will be seen that rotary systems are constituted on the one hand by parts 19 (including the pistons carried thereby), quill 15, extension 23, hub 27, spider 35, spring-pressed follower members 43, and follower rollers 47; and on the other hand, by parts 17 (including the pistons carried thereby), quill 13, extension 21, hub 25, spider 33, spring-pressed follower members 43', and the follower rollers 47'. Since these systems are identical in construction, their moments of inertia and natural frequencies of oscillation are the same, provided, as is the case, springs 85 and 85' are identical.

The term free pistons may be applied to the sets of pistons described because the relative motions between the groups of pistons on the respective rotors are determined by the algebraic sums of the compressive and expansive forces of the gaseous charges between them, and not by any geometrically determined motions imposed by any kinematically constrained linkage between them. This is irrespective of the fact that an average substantially constant velocity may be delivered from the pistons to the shaft 77 in view of the substantial moment of inertia of the shaft and parts driven thereby. Thus by the term free piston compressor, as used in the claims below, is meant a compressor having gas-controlled relative piston movements characterized by the absence from between the rotors carrying the pistons of any kinematically constraining linkage which might geometrically constrain the relative motions between the pistons. Their only constraint in my apparatus is variable and due to the actions of the reverse-locking mechanisms as determined by the momentums of the rotor systems, the gas buffering occurring during the collision events between pistons and the explosive forces.

The term alternating as applied to the pistons has the connotation, first, that the interdigitating groups of pistons alternate with one another in their interdigitated positions in the toroidal cylinder 1; second, that the piston groups alternate in moving and reverse-locking; and, third, that each piston alternates in functioning as an engine element in performing the power events in the arcuate engine section of the machine, and in functioning as a compressor element in passing through the arcuate compressor section of the machine.

It will be apparent that in both forms of the invention the toroidal or annular cylinder is characterized, as the case may be, by a power section (P or U) and a compressor section (G or V). It will also be apparent that if in either of the Fig. 3 or Fig. 6 forms of the invention the exhaust port (99 in Fig. 3; and 113 in Fig. 6) be disconnected from manifold 105 or 131, respectively, then the output from the air compressor section of the device will be delivered without exhaust gas dilution, as, for example, to an air pressure tank. The terms toroidal and annular as used herein are intended to refer to a cylinder such as 1, of any appropriate cross section.

It will be clear from the above that the invention can be carried out in machines employing other than eight or six pistons as shown, according to the principles above outlined for constructing the eight- and six-piston machines illustrated.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. A rotary internally powered compressor comprising an annular cylinder having fuel inlet and exhaust ports positioned substantially to subtend therein a power sector of one angle and having respectively adjacent air exhaust and inlet ports positioned substantially to subtend

a compressor sector of a substantially complementary angle completing a circle, piston-carrying rotors mounted for rotation relative to the cylinder and for free rotation relative to one another whereby either one of the rotors 5 may rotate in a forward direction at any one of various angular velocities while the other remains stationary, each rotor having at least one pair of pistons interdigitated in the cylinder with pistons of the other rotor, the members of each such pair being so angled on their respective rotor that the angle therebetween substantially equals said complementary angle, whereby said power and compressor sectors may thereby be separated by a pair of pistons at intervals during rotor movements, each rotor having additionally at least one other piston bisecting the power sector when its said other pair of pistons is in a sector-separating position, reverse-locking means for each rotor adapted to lock it against rotation in reverse direction and in response to reverse-acting torque on the rotor to hold it stationary in a position 15 wherein a said additional piston is in said bisecting position, whereby suction, compression, explosion and exhaust events may occur in said power sector when a pair of said angled pistons of the other rotor move therein, firing means adapted to initiate an explosion event to 20 motivate a reverse-locking event and a compression event adapted thereafter to terminate said reverse-locking event, a said additional piston of the other rotor during power events in the power sector being located for movement in the compressor sector to perform air suction and exhaust 25 events therein.

2. A rotary internally powered compressor according to claim 1, wherein said one angle is substantially 240° and said complementary angle is substantially 120°, and wherein there are three substantially equally spaced pistons 30 on each rotor.

3. A rotary internally powered compressor according to claim 2, including an air exhaust passage leading from said air exhaust port, and a burned-fuel exhaust passage leading from said fuel exhaust port, both of said exhaust 40 passages being joined to form a common heated supply of air and burned fuel exhaust issuing from the compressor.

4. A rotary internally powered compressor according to claim 1, wherein said one angle and said complementary angle both equal substantially 180° and wherein there are four substantially equally spaced pistons on each 45 rotor.

5. A rotary internally powered compressor according to claim 4, including an additional pair of adjacent air exhaust and inlet ports located on opposite sides of a line which divides said compressor sector into two substantially equal parts.

6. A rotary internally powered compressor according to claim 5, including air exhaust passages leading from said air exhaust ports, and a fuel exhaust passage leading from said fuel exhaust port, all of said exhaust passages being joined to form a common supply of air and burned-fuel exhaust issuing from the compressor.
